UNITED STATES PATENT OFFICE.

HERBERT J. McCUALEY, OF EAST AURORA, NEW YORK.

DESIGN FOR A MUD-GUARD FOR CYCLES.

58,246.

Specification for Design.

Patented June 28, 1921.

Application filed November 20, 1920. Serial No. 425,568. Term of patent 14 years.

To all whom it may concern:

Be it known that I, HERBERT J. McCUALEY, a citizen of the United States, residing at East Aurora, in the county of Erie and State of New York, have invented a new, original, and ornamental Design for a Mud-Guard for Cycles, of which the following is a specification, reference being had to the accompanying drawing, forming part thereof.

Figure 1 is a side elevation of a mud guard for cycles showing my new design. Fig. 2 is an end view of the same. Fig. 3 is a cross section thereof taken on line 3—3, Fig. 2.

I claim:

The ornamental design for a mud guard for cycles as shown.

HERBERT J. McCUALEY.
